(57) CLAIM

I claim the ornamental design for the article tissue box cover with offset segmented faces, as shown and described.

DESCRIPTION

FIG. 1 is a perspective view of one embodiment of a tissue box cover with offset segmented faces illustrating my new design;

FIG. 2 is a front elevational view thereof, it being understood that the undisclosed rear elevational view is identical thereto;

FIG. 3 is a left-side elevational view thereof, it being understood that the undisclosed right-side elevational view is identical thereto;

FIG. 4 is a top plan view thereof;

FIG. 5 is a bottom plan view thereof;

FIG. 6 is a perspective view of an alternative embodiment of a tissue box cover with offset segmented faces formed partially with wood grain surface appearances and showing my new design;

FIG. 7 is a front elevational view thereof, it being understood that the undisclosed rear elevational view is identical thereto;

FIG. 8 is a left-side elevational view thereof, it being understood that the undisclosed right-side elevational view is identical thereto;

FIG. 9 is a top plan view thereof;

FIG. 10 is a bottom plan view thereof;

FIG. 11 is a perspective view of an another alternative embodiment of a tissue box cover with offset segmented faces having smooth, plain surfaces and showing my new design;

FIG. 12 is a front elevational view thereof, it being understood that the undisclosed rear elevational view is identical thereto; and

FIG. 13 is a left-side elevational view thereof, it being understood that the undisclosed right-side elevational view is identical thereto.

FIG. 14 is a top plan view thereof; and,

FIG. 15 is a bottom plan view thereof.
